UNITED STATES PATENT OFFICE.

JAMES WILBUR KYLE, OF MEMPHIS, TENNESSEE.

PENCIL-HOLDER.

1,101,456.

Specification of Letters Patent. Patented June 23, 1914.

Application filed November 7, 1913. Serial No. 799,692.

To all whom it may concern:

Be it known that I, JAMES W. KYLE, a citizen of the United States, and a resident of Memphis, in the county of Shelby and 5 State of Tennessee, have invented a new and Improved Pencil-Holder, of which the following is a full, clear, and exact description.

Among the principal objects which the present invention has in view are: to provide a device of the character named, simple, efficient and economical in construction; and to provide means for adapting a holder so constructed to hold pencils or similar objects of different diameters.

15 In the drawings: Figure 1 is a view showing a pencil supported upon a garment by means of a holder constructed and arranged in accordance with the present invention; Fig. 2 is a vertical section taken on the line 20 2-2 in Fig. 1; Fig. 3 is a perspective view of a pencil-holder constructed in accordance with the present disclosure.

As shown in the drawings, a pencil, 8, when supported by the present holder, extends through a ring 9, and rests against a half-loop 10. Said ring and loop are connected by a spring wire section 11, which normally holds the half-loop 10 out of line with the axis of the ring 9. The ring 9 is 25 made full-sized, to permit a pencil such as indicated by the numeral 8, to pass freely therethrough. The office of the half-loop 10 and spring wire section 11 is to cant the pencil within the ring 9, to frictionally engage the opposite sides of said ring, as shown 30 best in Fig. 1 of the drawings. Normally, the section 11 holds the half-loop 10 sufficiently removed to one side of the axis of the ring 9 to bind a small pencil within said 40 ring.

The ring 9, half-loop 10 and section 11 are supported on a garment of personal wear, by a spiral pin 12, the sharpened point 13 of which is arranged to penetrate the cloth of 45 a garment when the body of the pin following thereafter is in effect screwed through said cloth. The coil of the pin 12 is flat, to form a backing to prevent the withdrawal of the pin when the shank 14 extends 50 through the cloth. The shank 14 of the pin 12 is concentric with the coil of said spring, and forms the support for the wrapping 15 of the section 11 and ring 9.

55 The elements above mentioned are all constructed from a single piece of spring wire, one end of which is sharpened to form the

pin-point 13, and the other ends of which is bent back upon itself to form a blunt end 16 on the half-loop 10.

In constructing the device, the wire is first 60 bent upon itself to form the ring 9. One portion of the wire is then twisted over the other to form the wrapping 15. The portion contained within the wrapping 15 is the shank 14 of the attaching pin. The wrapping 15 is regulated to extend the section 11 65 at a decided angle to the plane of the ring 9. At the lower end of the section 11, the wire is bent to form the half-loop 10 to extend outward from said section 11 on the same 70 side as the ring 9. The half-loop 10 is then completed by folding the wire back upon itself to make the blunt end 16. In disposing the ring 9 and the half-loop 10, they are arranged so that the half-loop 10 may swing 75 below said ring to a position coaxial therewith. The pin 12 is formed by bending the wire forming the shank 14 substantially as shown in Fig. 3 of the drawings, said shank being concentric with the coil of the spring, 80 while the point 13 is preferably advanced slightly into a position tangential with the coil.

To employ the device, it is first mounted 85 on the garment by inserting the point 13 in the cloth; then, by forcing the body of the pin 12 through the cloth, employing a screwing action therefor, the body of the pin is inserted within the cloth, and then adjusted until the shank 14 coincides with the perforation in the cloth. In this position, it 90 will be found, the lower end of the section 11 rests against the garment, while the half-loop extends upward therefrom. If, in the normal position, the section 11 hangs vertical, it will be found that the ring 9 is slanted. When a pencil is now inserted into the ring 9, the operator holds the half-loop 10 while he moves the lower extension of the pencil below the ring 9 to the outside of and past 95 the half-loop 10, until it can be placed within the hollow or inner curve of said half-loop 10. In thus moving the pencil, it will be seen, the operator has placed a torsional strain on the ring 9 and wrapping 15. The 100 immediate result of this is to grip the pencil at three points, two of which are at opposite sides of the ring, and the third point, the half-loop 10.

110 It is evident that when it is desired to remove the pencil from the holder, this is readily accomplished by disengaging the

half-loop 10 from the pencil, when the same will swing freely to a position substantially coaxial with the ring 9 in its normal position, and can be lifted therefrom.

5 Claims:

1. A pencil holder, comprising a ring; a resilient member structurally united with said ring and extending therefrom in a plane perpendicular to the plane of said ring; a member set out from said resilient member, adapted to bear against the side of a pencil, when held within and extending below said ring; and a pin having a spiral coil and a sharpened point for insertion through the fabric of a garment of personal wear.
- 10 2. A pencil holder formed from a single piece of spring wire, shaped to comprise a

ring; a pin having a pointed end and a spirally-coiled body; and a spring section extending in a plane approximately perpendicular to the plane of said ring and having at the free end thereof a half-loop section disposed perpendicular thereto, adapted to be moved to coincide axially with said ring, the normal position of said half-loop being out of coincidence with the axis of said ring.

In testimony whereof I have signed my name to this specification in the presence of two subscribing witnesses.

JAMES WILBUR KYLE.
